UNITED STATES PATENT OFFICE

GEORGE F. RHEA, OF GREENEVILLE, TENNESSEE

WIRE AND PICK HOLDER FOR FLORISTS

Application filed January 5, 1929. Serial No. 330,685.

This invention relates to devices for holding the wires and "picks" used by florists in making up floral designs such as funeral wreaths and the like.

5 The general object of the invention is to provide a wire holder of this character which is convenient, which is relatively light and which is capable of holding wires of various lengths and wired picks or wooden pins.

10 A further object is to provide a construction of this character having compartments for the wires, each compartment being for wires of a certain length and having spring holders within which a bunch of "picks" may 15 be placed and held conveniently for the florist and from which the picks may be withdrawn one by one as they are desired to be used and in this connection to provide a construction of such character that no picks will be lost, 20 that is, dropped from the machine as the picks are withdrawn therefrom.

Other objects will appear in the course of the following description.

My invention is illustrated in the accompanying drawings, wherein:

25 Figure 1 is a top plan view of a wire and pick holder constructed in accordance with my invention;

Figure 2 is a vertical section on the line 20 2—2 of Figure 1—

Figure 3 is a vertical section on the line 3—3 of Figure 1;

Figure 4 is a front elevation of the completed structure;

35 Figure 5 is a cross section on the line 5—5 of Figure 2.

Referring to these drawings, 10 designates a base formed in the shape of a pan and having upstanding sides. This is made of sheet 40 metal and disposed in the bottom of the pan is preferably a plate of heavier metal 11 which is riveted to the pan. Mounted upon this plate by soldering, riveting or otherwise is a preferably sheet metal casing 12 divided by one or more partitions 13 into any desired number of compartments. These compartments are open at the top. Projecting 45 radially outward from the rounded outer face of the casing 12 are the walls of vertical compartments 14 which are open at the top and

extend down to the base. There may be any number of these compartments and each compartment is designed to contain a different length of wire such as is used by florists. Each compartment will preferably have upon its face a card holder 15 within which a card indicating the number of the wire, that is, the length thereof will be placed in that compartment.

55 Each compartment will have a different effective length which may be secured by filling the lower end of the compartment with different thicknesses of paper or other filling material.

Attached to the front walls of the compartments 14 by riveting or otherwise is a strap 16 and attached adjacent their upper ends to this strap are the brackets 17 of relatively heavy iron, the lower ends of these brackets being flanged at 18 and riveted to the base 70 while the upper ends of the brackets are bent forward and downward slightly above the strap 16 as at 19. Mounted upon the angular ends 19 are receptacles 20 for picks, these receptacles being formed of sheet metal and 75 as illustrated in Figure 5 having a flat bottom, and upwardly extending sides which, at a certain distance above the bottom, flare outwardly as at 21. These flared portions are preferably rounded as to their edges and the pick holder 20 is open at its opposite ends and is carried in a downwardly and forwardly inclined position. A rubber pad 22 is preferably disposed along the bottom of the pick holder.

85 Associated with each pick holder is a spring clamp formed as follows:—Attached to the front of the casing 12 just above the upper ends of the compartments 14 is a pintle 23 and mounted upon this pintle are a plurality of clamping arms 24 which extend upward and radially outward in a slight bow and at their forward ends are extended downward and engage against the pad 22 in the bottom of the corresponding holder. The lower end 90 of each arm is transversely recessed to receive a rubber pad 25. Each arm is resiliently urged downward by a spring 26.

100 This spring at its lower end is operatively connected to the base, as for instance, by the

wire 27 which is soldered to the base and at its upper end, each spring is operatively connected to a loop-like yoke 28 which extends upward just forward of the bracket 17 and embraces the rear end of the corresponding holder and at its upper end extends over the arm 24 and is engaged therewith by means of a bead 29. Thus each clamping arm is urged downward toward the bottom of the bottom of the holder by means of a spring and thus acts to clamp picks within the holder. Each holder 20 is designed to contain picks of different lengths, some smaller and some larger and each pick as usual is of wood with a length of wire attached to the butt end thereof. Some of these picks are six inches long and other picks decrease in size from this maximum length. There are four different sizes of picks ordinarily used and six different sizes of wire commonly used. I have illustrated compartments for six different lengths of wires, and it is to be understood that preferably six compartments will be formed for six different lengths of wires.

In the use of this device, the holders 20 are filled with the appropriate sized picks and the compartments 14 and the compartments in the casing 12 are filled with the appropriate lengths of wire. Then as the florist needs the picks or wires, he withdraws them from the holders or compartments. The clamping action of the member 24 is such that the picks are held firmly in place and yet may be readily withdrawn from time to time as the user wishes them without any chance of the picks being dropped from the machine when a pick is withdrawn.

Other pick holders known to me and used to a slight extent by florists are impractical for the reason that when one pick is pulled out of the device, other picks are liable to drop out also and be lost on the floor and thus there is a relatively great waste of picks. My holder holds all four sizes of picks commonly used by florists. The pick holder above referred to holds two sizes of picks and grips the wires attached to the picks by metal jaws whereas with my device, the rubber pad 22 and the rubber pad 25 at the lower end of the jaw 24 grips these wires or the wooden picks themselves very firmly and yet permits the ready withdrawal of the wires from the picks or grips.

Another advantage of my construction is that it is relatively light and thus can be moved about easily. Furthermore my device is compact and takes up but little room.

The metal pan constituting the base of the device is particularly useful for holding pliers, wire snips, thread and spooled wire.

While I have illustrated a construction which I have found to be particularly useful for the purpose intended, I do not wish to be limited thereto as it is obvious that the device is susceptible of many changes in form

without departing from the spirit of the invention as defined in the appended claims.

I claim:

1. A holder for florists' picks and wire comprising a base, vertical wire receptacles at different depths extending upward from the base and open at the top and designed to contain wire of different lengths and pick holders mounted upon the receptacles and including an element having laterally flaring sides to receive the picks, and a resiliently actuated clamp associated with the element and yieldingly urged toward the bottom thereof. 70

2. A holder for florists' picks and wire comprising a base, wire receptacles extending upward from the base and open from the top and designed to contain wire of different lengths and pick holders mounted upon the receptacles and including an element having laterally flaring sides to receive the picks, and a resiliently actuated clamp associated with the element and yieldingly urged toward the bottom thereof, said clamp being pivoted at its rear end. 80

3. A holder for florists' picks and wire comprising a base, wire receptacles extending upward from the base and open at the top and designed to contain wire of different lengths and pick holders mounted upon the receptacles and including an approximately horizontal element extending outward from the wire receptacles and having laterally flaring sides to receive the picks and a resiliently actuated clamp disposed above and associated with the element and yieldingly urged toward the bottom thereof, the bottom of the receptacle being provided with a rubber pad, the extremity of the clamp being transversely recessed. 90

4. A holder for florists' picks and wire comprising a plurality of vertically disposed receptacles connected to each other and open at the top and a plurality of pick holders mounted upon and projecting from said receptacles, each of said holders being formed to provide an approximately horizontal channel-shaped element extending away from the receptacles and having flaring side walls and open at front and rear, and a clamp associated with each holder, each clamp being hingedly mounted upon said receptacles and having its forward end extended downward into said holder, and a spring urging the clamp downward toward the bottom of the holder. 105

5. A holder for florists' picks and wire comprising a plurality of vertically disposed receptacles connected to each other and open at top and a plurality of pick holders mounted upon and projecting from said receptacles, each of said holders being formed to provide a channel-shaped element having flaring side walls and open at front and rear, and a clamp associated with each holder, each clamp being hingedly mounted upon said receptacles. 115

tacles and having its forward end extended downward into said holder, and a spring urging the clamp downward toward the bottom of the holder, said spring being connected at one end to the base, and a yoke engaging over the clamp and engaged with said spring.

6. A device of the character described, comprising a pan-shaped base, a plurality of connected vertically disposed wire receptacles mounted upon the base and upstanding therefrom and open at the top, each receptacle being designed to contain wires of different lengths, certain of the receptacles extending above certain of the other receptacles, a plurality of brackets mounted upon the base and upon the front walls of the receptacles, the brackets being inclined downwardly and forwardly, pick holders mounted upon said brackets, each holder being channel-shaped and having outwardly and upwardly inclined walls and being open at its ends, and clamps associated with each holder, each clamp comprising a clamping arm pivotally mounted at its rear end upon a wall of one of said receptacles and extending forward and then downward into the holder and contractile springs attached to the base and operatively engaging said arms and urging the arms downward.

7. A device of the character described, comprising a pan-shaped base, a casing extending upward from the base and divided into receptacles open at the top, a plurality of radially disposed receptacles mounted upon the pan and disposed against the front wall of the casing but being less in height than the said front wall of the casing, all of said receptacles being adapted to contain different lengths of florists' wire, a plurality of brackets mounted between said radially projecting receptacles and extending outward and downward therefrom, a plurality of pick holders mounted upon said brackets, each pick holder being channel-shaped and having upwardly and laterally flaring walls and being open at its ends, and clamping arms hingedly mounted upon the front wall of the casing and extending forward and downward into the corresponding holder, and contractile springs urging said arms downward toward the bottom of the holder.

8. A holder for florists' picks including an approximately horizontal element having laterally flaring sides to receive the picks and a yieldable bottom pad and a resiliently actuated clamp associated with the element and yieldingly urged toward the bottom thereof, said clamp being transversely recessed.

60 In testimony whereof I hereunto affix my signature.

GEORGE F. RHEA.
